UNITED STATES PATENT OFFICE.

JOHN N. SCISM, OF NEW YORK, N. Y.

BENDING-TOOL.

1,159,806.

Specification of Letters Patent.

Patented Nov. 9, 1915.

Application filed March 9, 1912. Serial No. 682,605.

To all whom it may concern:

Be it known that I, JOHN N. SCISM, a citizen of the United States, residing in the city of New York, borough of Brooklyn, county of Kings, and State of New York, have invented a certain new and useful Bending-Tool, of which the following is a specification.

This invention is a bending tool, the same being adapted for bending the end portion of a metal pipe, and, more particularly, to so prepare the end portion of an iron conduit pipe that is adapted to be coupled to a box or other element, whereby the bent end pipe may be used as a part of an electrical wiring installation for a building, etc.

The present practice of installing electrical wire conduits requires the use of tools for cutting threads on the end portions of the conduit pipes for the purpose of coupling said pipes. Such tools are slow and expensive in operation, particularly when the threading dies must be kept in a sharpened condition, and well oiled when in use, but this threading operation often requires the services of two men, and involves the use of additional appliances, such as a vise for holding the pipe rigidly in position. Even after the thread cutting operation shall have been completed, the pipe must be reamed.

The present invention overcomes the disadvantages specified and others, for the reason that it affords means for easily and quickly preparing the end of a pipe so that it may be coupled to a box or other element, whereby the pipe may be used as a part of a wiring conduit substantially as disclosed in a prior application filed by me on December 21, 1911, Serial No. 667,146, for an invention entitled junction box couplings for electrical conduits.

The tool of the present invention embodies a structure which is simple in construction and effective in operation. The tool is easily operated by hand and by a single workman while engaged on the job of installing a wiring conduit, thus enabling many of the bending operations to be quickly performed without resorting to the use of a vise to clamp the pipe rigidly in position prior to and during the bending operation. Furthermore, the end portion of the pipe can be more easily prepared, and in less time, than by the common method of cutting a thread on the pipe. Again, any

desired number of lips can be bent on the pipe end, or enough lips can be bent to produce a substantially continuous flange on the pipe, and in this latter event, the pipe does not require to be reamed in order to produce a smooth inner surface through which the wires can be introduced and drawn with facility and without cutting them.

The invention consists of a lever provided with means for bending a lip on the end of a pipe.

It consists, further, of a lever provided with bending means and with limiting or stop means for arresting the movement of the lever.

Other features and advantages of the invention will appear from the annexed detailed description.

In the accompanying drawings, I have illustrated different practical embodiments of the invention, but the constructions shown therein are to be understood as illustrative, only, and not as defining the limits of the invention.

Figure 1 is a side elevation of a bending tool constructed in accordance with this invention, a part of said tool being shown in vertical section and a part of a pipe being shown in elevation and in section, the tool being positioned ready to bend a lip upon the pipe. Fig. 2 is a horizontal section on the line 2—2 of Fig. 1 through the tool, the pipe to be operated upon being shown in plan. Fig. 3 is a view similar to Fig. 1 illustrating another embodiment of the bending tool in operative relation to a portion of a pipe, the tool being shown in the position which it assumes after bending a lip upon the pipe, which lip is shown in section in said figure. Fig. 4 is a horizontal section through the tool on the line 4—4 of Fig. 3, the pipe and the bent lip thereof being shown in plan, one of the jaws being omitted. Fig. 5 is a side elevation of a double tool head adapted to produce two sets of complementary jaws, for the purpose of bending pipes, the walls of which vary in thickness. Fig. 6 is a plan view of another form of tool embodying the invention. Fig. 7 is a transverse section on the line 7—7 of Fig. 6. Fig. 8 is a side elevation, partly in vertical section, illustrating the tool of Figs. 6 and 7 applied in operative position to the end portion of a pipe, the plane of the section in Fig. 8 being indicated by the dotted

line 8—8 of Fig. 6. Fig. 9 is an under or bottom plan view of the device shown in Figs. 6, 7 and 8. Fig. 10 is a side elevation, partly in section, illustrating another embodiment of a tool somewhat similar to Fig. 8, but illustrating the employment of two levers and two sets of bending jaws in conjunction with a single fulcrum block. Fig. 11 is a detail view in plan of a part of the 10 divided and pivoted fulcrum block employed in the construction of Fig. 10. Fig. 12 is a side elevation, partly broken away, and in section, illustrating another form of the bending tool in operative position upon 15 an end portion of a pipe for the purpose of bending the latter to produce one or more lips thereon. Fig. 13 is a bottom plan view of the device shown in Fig. 12, the pipe being shown in plan. Fig. 14 is an end view 20 in elevation of the fulcrum block employed in the construction of Figs. 12 and 13. Fig. 15 is a side elevation, partly in vertical section, of a still further embodiment of the invention applied to the end portion of a 25 pipe, illustrating the operation of bending a lip on said end of the pipe, one of the jaws of the bending tool being adapted for contact with the inner surface of a pipe for the purpose of limiting or arresting the movement 30 of the lever in the operation of bending the lip on said pipe. Fig. 16 is an under or bottom plan view of the tool illustrated in Fig. 17, the position of the tool with respect to the pipe being shown in full lines. 35 Fig. 17 is a side elevation of a still further embodiment of the invention wherein the tool is provided with a double head adapted for operation upon a pipe the walls of which vary in thickness. Fig. 18 is a side elevation 40 of a still further embodiment of the invention wherein the lever has a cam action upon the bending jaws. Fig. 19 is a side elevation, partly in vertical section, of a still further embodiment of the invention, the 45 tool being shown in the position which the parts assume after bending the lip upon the end of a pipe. Figs. 20, 21 and 22 are a bottom plan view, a side elevation, and an 50 end view of a jaw adapted to serve as the fulcrum for the lever when bending a lip upon a pipe end. Fig. 23 is an end view of the pipe, the full lines illustrating a lip formed upon the pipe and the dotted lines 55 illustrating the operations of bending a succession of the lips in order to produce a substantially continuous flange upon the pipe end.

The tool illustrated in Figs. 1 and 2 embodies a lever A, a fulcrum member B, and two coöperating jaws C, D, jaw C being illustrated as a part of lever A, whereas jaw D is a part of fulcrum member B. As shown, the fulcrum member is a block or casting adapted to support lever A in operative relation to an end portion of pipe

X. The fulcrum block is provided with an inner curved face b, the curvature of which corresponds substantially to the external curvature of the pipe upon which the tool is to operate, and this fulcrum block is provided at its lower portion with a foot-piece b', and near its upper portion with an internal rib b², said fulcrum rib being positioned transversely upon the inner face of the fulcrum block, and said rib being formed with two inclined faces meeting at an apex. The fulcrum block is enlarged at its upper external portion so as to produce a curved bearing surface b³. Lever A may be of any desired form and dimensions, and at one end portion of the lever it is so formed as to produce a laterally extending jaw C. The inner face of this jaw C is curved at c to conform to the curvature of the inner surface of the pipe upon which the tool is to operate, and at the upper part of this curved surface the jaw is provided with a ledge or shoulder c' adapted to rest upon the top edge of pipe X, for the purpose of limiting the movement of the jaw when inserted into the pipe, whereby the tool is adapted to be accurately positioned upon the end portion of the pipe when said tool is initially applied thereto. Lever A at one side of the jaw is enlarged at a, and an edge portion of this enlarged part of the lever is curved or rounded at a', thereby forming a bearing edge, the arc of which is concentric to the bearing edge b³ of fulcrum block B, said edges b³, a' of the fulcrum block and the lever respectively being struck from a center positioned at the apex of the bending rib b² on the fulcrum block, whereby the lever A is adapted to move in an arc of a circle having its center at the apex of the double beveled rib b². The lever A and the fulcrum block are operatively connected by plates E positioned at the respective sides of the lever and the fulcrum block. Said plates are fastened rigidly to the enlarged part a of the lever by screws, rivets, or other equivalents e, and these plates are provided with curved slots e'. The slotted parts of plates E lap over the enlarged curved part b³ of the fulcrum block, and said fulcrum block is provided with studs or a pin e², which engage with the plates E so that the parts are connected loosely together for the purpose of permitting the lever to have the desired movement relative to the fulcrum block.

The operation of the tool shown in Figs. 1 and 2 is as follows: The tool is fitted to the end portion of pipe X by inserting jaw C into the end of the pipe until its movement is arrested by ledge c'. The fulcrum block B is positioned upon the outside of the pipe, the foot-piece b' resting upon said pipe and the rib b² being in contact with the pipe near the open end thereof. Pressure is applied to lever A in the direction indicated by the

arrow α , the effect of which is to cause the curved edge a' of the lever to ride upon the curved edge b^3 of the fulcrum block, and to cause jaw C to press upon that part of the pipe above rib b^2 on the fulcrum block. The lever at the completion of the bending operation assumes an inclined position substantially as shown by the lever of Fig. 3, whereby the fulcrum block is pressed into firm engagement with the pipe and jaw C operates upon an end portion of the pipe to bend said end portion outwardly until the edge of the pipe is brought into contact with the surface d of the bearing block above rib b^2 , thus resulting in the production of a lip upon the end portion of the pipe. The tool may be shifted part way around the pipe in order to assume another operative position upon said pipe, for the purpose of bending another lip thereon, and this operation of successively bending the pipe by the application of pressure to the tool may be repeated indefinitely until a substantially continuous flange is produced on the end portion of the pipe.

The bending tool shown in Figs. 3 and 4 is quite similar in construction and operation to the tool of Figs. 1 and 2. Fulcrum block B' and lever A' are operatively connected by plates E' . The fulcrum block is provided with the curved bearing rib b^3 , and lever A' is provided with jaw C' and with a curved bearing edge a' , the curvature of the edges b^3, a' being in arcs of circles struck near the center of a lip or shoulder b^4 , similar in some respects to the rib b^2 of the block B in Fig. 1, whereby the edge a' of the lever is adapted to have firm bearing upon edge b^3 of the fulcrum block. The inner face of fulcrum block B is curved to conform to the external curvature of the pipe X , and said inner bearing face is cut away at its upper part to form jaw D' , a part of the inner face of block B' being serrated at b^5 , in order to have gripping engagement with the exterior surface of the pipe. Jaw C' is provided with a stop shoulder c' . The enlarged bearing portion b^3 of the bearing block is formed with laterally extending flanges or ribs f , the inner edges of which are curved concentrically to the edges b^3, a' . Plates E' are secured firmly at e to an enlarged part a of the lever, and these plates are provided with in-turned flanges f' , the latter snugly embracing the flanges f on the fulcrum block, as shown in Fig. 4, whereby the lever A' and fulcrum block B' are operatively connected together.

When the tool of Figs. 3 and 4 is positioned upon the pipe, block B' engages with the exterior surface of the pipe, and jaw C' enters the end portion of the pipe, the entering movement of the jaw being arrested by shoulder c' . The lever being in a horizontal position, and at a right angle to the pipe,

pressure is applied to said lever to move it in the direction indicated by the arrow α , whereby the jaw C' exerts pressure internally of the pipe and upon an end portion thereof, for the purpose of forcing a part of the pipe wall in an outward direction, and into contact with jaw D' , thus producing a lip upon the end portion of the pipe.

It should be noted that when the lever of the tools shown in Figs. 1 and 3 is pressed in a downward direction, the bearing edge a' of the lever rides upon the bearing edge b^3 of the fulcrum block, but the desired movement of the lever in the operation of bending the lip on the pipe is limited or arrested by the lip on the pipe coming into contact with the surface d on the fulcrum block. This contact of the lip with the surface d of the fulcrum block limits the movement of the lever in the direction required to bend the end of the pipe to produce said lip thereon, and the operation of the lever is thus rendered uniform in bending successive lips on the pipe, as a result of which all the lips will be bent uniformly and regularly so as to insure a good job of work, whereby the bent end of the pipe is adapted for use in connection with coupling means, for the purpose of attaching said bent end of the pipe to a junction box or other element, substantially as disclosed in my prior application.

The tool illustrated in Figs. 6, 7, 8 and 9 of the drawings embodies the generic elements of the lever and the fulcrum block, substantially as hereinbefore described, said lever in these figures of the drawings being indicated at F , and the fulcrum block at G . The fulcrum block is adapted to be positioned externally upon the end portion of the pipe, and for this purpose said block is provided in its under face with a recess g , the diameter of which somewhat exceeds the external diameter of pipe X upon which the tool is to operate. The recess g is partly closed at the top of the fulcrum block by flange g' , said flange being adapted to rest upon the end face of the pipe, as shown in dotted lines in Fig. 8. The fulcrum block is slotted or cut away at one side at g^2 , and through this slot or cut away portion of the block extends a jaw H , the latter being applied to the under side of lever F , and secured rigidly thereto by a screw h . Lever F is formed at one end to provide a jaw I , the jaws H, I , corresponding to the jaws C, D of Fig. 1, and the jaws C', D' of Fig. 3. Jaw I on the end of the lever is extended through the opening formed by the flange g' at the top of fulcrum block G , so that jaw I is adapted to extend into the pipe for the purpose of contacting with one wall thereof when the tool is placed in operative position upon said pipe. The lever and the fulcrum block are operatively connected by a strap J , the latter embracing lever F at a point

adjacent to jaw I, and said strap being attached rigidly to the lever by rivets j or equivalent fastenings. The end portions of the strap are extended beyond the lever so as to have lapping relation to the sides of fulcrum block G, and said strap is attached pivotally to the fulcrum block by pins or rivets j' . The jaw H extends into the slot g^2 of the fulcrum block so as to lie below an abutment G' of said block. The free end of said jaw H is curved to conform to the external surface of the pipe, said free end of the jaw being adapted to contact with said pipe at a point below the extremity or end face of the pipe. The lever is adapted to swing in an arc of a circle struck from the end face of jaw H, the pivots j' being positioned in the plane of the end of jaw H on which the lever is adapted to swing as a center. Jaw I on the end portion of the lever is of sufficient length to extend well down into the pipe, and when the lever is moved from its horizontal initial position to its final operative position, the jaw I is adapted to contact with the inner surface of the pipe, for the purpose of acting as a stop in arresting the bending movement of the lever.

The operation of the tool shown in Figs. 6, 7, 8, and 9 is as follows: The fulcrum block is slipped over the end of the pipe so that flange g' will rest upon said end of the pipe to limit the introduction of jaw I into the pipe, and accurately determine the position of the tool with relation to said pipe. The jaw H is in contact externally with the pipe and the lever extends outwardly from the pipe substantially at right angles thereto. Pressure is applied to the lever to force it in the direction indicated by the arrow x in Fig. 8, and thus the jaw I exerts pressure upon an end portion of the pipe for the purpose of bending said end portion of the pipe in an outward direction until the edge of the pipe contacts with the abutment G' of the fulcrum block. The lever swings on the center afforded by pivot j' and by the free end of jaw H, the latter acting as the real fulcrum for the lever, so that the pipe will be bent outwardly from the lower edge of said jaw H. The lever is returned to a horizontal position, in order to release the tool from the bent pipe, and the tool may then be shifted around the pipe to another operative position, the operations being repeated as many times as it is desired to produce lips upon the end of the pipe. It should be noted that fulcrum block G is provided at its under side with a plate h' , the latter being positioned at the opposite side of the block from jaw H. This plate h' is fastened firmly to the block and it is positioned for engagement with pipe X so as to assist in determining the position of the tool when applied to the pipe end.

In Figs. 10 and 11 I have illustrated a form of tool somewhat similar to that of Figs. 6 to 9, inclusive, except that two levers F', F² are used in conjunction with a fulcrum block G². This fulcrum block is divided or split centrally on the line indicated at g^3 , thus producing two members which are hingedly or pivotally connected at g^4 . The split or hinged fulcrum block is adapted to be opened or spread in order to apply the tool to the end portion of a pipe, said fulcrum block being provided with a recess similar to the recess g , and with a flange similar to the flange g' , in order that the fulcrum block may be operatively positioned upon the end portion of pipe X. The levers F', F² are provided with straps similar to the strap J, and these levers are connected with the fulcrum block at the respective sides of the hinge g^4 . Each lever is provided with a jaw similar to the jaw I, and internally of the fulcrum block is an abutment g^5 serving the purposes of jaw H. When the tool of Figs. 10 and 11 is applied to the end portion of pipe X, the jaws I of said levers extend into the pipe. Pressure may be applied simultaneously to the levers, for the purpose of moving them from horizontal positions to the inclined position shown in Fig. 10, and thus the jaws I exert pressure simultaneously upon two parts of the pipe, for the purpose of bending said pipe outwardly, the bent portion of the pipe beginning at the abutment g^5 and inclining outwardly until the edge of the pipe comes in contact with the inner surface of the block, after which the levers are returned to their horizontal positions, and the tool may then be shifted to a new operative position upon the pipe, or it may be removed therefrom.

The tool shown in Figs. 12, 13 and 14 of the drawings embodies a lever K and a fulcrum block L corresponding in a generic sense to the levers and fulcrum blocks heretofore described, except that fulcrum block L is adapted to be positioned partly within and partly without the pipe. This fulcrum block L consists of a substantially cylindrical member provided at its upper part with an enlarged flange l , said flange being enlarged at one side to form a depending foot-piece l' , the latter being adapted to limit the outward bending of the lip. The block L is provided with a recess m and with a curved bearing face m' . Lever K is enlarged at one end to form a jaw M adapted to extend into the recess m of the fulcrum block. The lower part of this jaw is enlarged and provided with a curved edge m^2 , said curved edge being fitted snugly into contact with the curved bearing face m' , whereby the jaw and the lever are adapted to turn within the recessed part of block L. Lever K is provided with a strap N

attached rigidly thereto by rivets *n*. The legs of the strap extend downwardly into overlapping relation to the depending foot-piece *l'* of the block, and said legs of the strap are connected pivotally by rivets *n* to the foot-piece of the bearing block, thus operatively connecting the lever and the bearing block. The enlarged part *l* of the bearing block is provided with another recess *o*, the face of which forms an abutment *o'*.

When using the tool of Figs. 12, 13 and 14, the block *L* is slipped into the end of the pipe until flange *l* rests upon said pipe. Lever *K* may be depressed to an inclined position, thereby causing jaw *M* to exert pressure upon the end of the pipe, so as to force a part of the pipe outwardly until it comes into contact with abutment *o'*, thus resulting in the production of a lip upon the end portion of the pipe. Obviously, the lever may be raised and the tool shifted to a new position, or said tool may be withdrawn from the pipe.

The tool illustrated in Fig. 15 is quite similar to some forms of the tool heretofore described. It embodies a lever *P* and a fulcrum block *Q*. This fulcrum block is adapted to be positioned externally upon and in contact with pipe *X*. The upper part of block *Q* is slotted at *q* and above this slot the block is provided with a ledge *q'* and an abutment *Q'*. Lever *P* is formed at one end to produce a jaw *P'*, the length of said jaw being such that it will contact with the inner surface of the pipe when the lever is pressed to an inclined operative position, whereby the jaw *P'* operates to bend the end portion of the pipe until the resulting lip contacts with the abutment *Q'*, the lower extremity of the jaw *P'* operating by its contact with the inner surface of the pipe to limit the movement of the lever, and correspondingly limit the bending of the pipe to produce the lip thereon. The fulcrum block *Q* and lever *P* are operatively connected by plate *R*, the latter being secured firmly to the lever by a screw *r*. The plate *R* extends into the slot *q* of fulcrum block *Q*, and a pin *r'* passes through the fulcrum block of the plate *R* so as to pivotally connect the lever and the fulcrum block. The operation of the tool will be readily apparent from the preceding description.

The tool illustrated in Figs. 16, 17, 20, 21 and 22 embodies a set of complementary jaws or two sets of complementary jaws, one jaw of each set being constructed in the novel manner shown in Figs. 20 to 22, inclusive. I will describe the tool as having a double head, substantially shown in Figs. 5 and 17, but it will be understood that a single head may be employed. Lever *S* is enlarged at one end portion so as to produce a head *s* and two jaws *T*, *T'*, said jaws extending

in opposite directions from head *s*. Each jaw is provided with an inner convex face *t*, and when one jaw or the other is thrust into the end portion of a pipe, the convex face *t* is adapted to contact with the inner surface of said pipe. *U*, *U'* are jaws made separate from the lever and attached firmly thereto in positions to coöperate with jaws *T*, *T'*, respectively. As shown, the separable jaws *U*, *U'* are seated in recessed parts *s'* of the lever, and said jaws are fastened firmly to the lever by a single bolt *u* and a nut *u'*, said bolt passing through the jaws and the lever in a manner to secure jaws *U*, *U'* in immovable relation to the lever and the coöperating jaws *T*, *T'*. Each jaw *U*, *U'* is provided with an operative end constructed in the manner shown in Figs. 20 to 22, inclusive. The operative end of the jaw is curved to produce a concave face *v*, and said operative end is provided with a flange *v'*, said flange being at an obtuse angle to the under face *v*. The concave face *v* on the end of the jaw is perpendicular to the under face *v* of said jaw, whereas the face of the flange *v'* is at an obtuse angle to the under face *v*. The operative end of the jaw thus has two differently positioned faces, as indicated in full lines in Fig. 20, and in dotted lines in Figs. 21 and 22. The inclined face of the flange *v'* acts as a fulcrum for the lever when the tool is positioned in engagement with the pipe, and the perpendicular curved face of said jaw acts as an abutment in limiting the bending of the lip upon the pipe end.

In Fig. 17 the jaw *U* coöperates with the jaw *T*, so that the tool is adapted to be positioned upon a pipe of one size, say one-half inch in diameter, for the purpose of bending a lip on this particular size of pipe, whereas the jaws *U'* and *T'* are positioned in such relation to each other that they will operate upon a pipe of a different diameter, say a three-quarter inch pipe. Obviously, the pipes of different diameters have walls of different thicknesses, and the jaws *U*, *T*, as well as the jaws *U'*, *T'*, are so spaced that they will accommodate themselves to the different thicknesses of the pipes of different diameters. When the tool is placed upon a pipe of a given diameter having a wall of predetermined thickness, the end portion of the pipe is positioned between the complementary jaws. When pressure is applied to the lever, the outer jaw acts as the fulcrum and the inner jaw exerts pressure upon the pipe, the result of which is to bend a lip on the pipe, the deflection of the metal in the operation of bending the lip being determined by the curved face upon the operative end of the outer jaw.

In Fig. 18 the tool embodies a member *W* having a jaw *w*, a lever *W'* and a sliding jaw *W*. The member *W* is provided with

a strap w' attached rigidly thereto and embracing the sliding jaw W^2 . The operative end of this jaw W^2 coöperates with the jaw w , and said slideable jaw is retained in operative position by a spring w^3 , the latter being preferably a leaf spring secured in the member W . Lever W' is fulcrumed at w^3 on member W , and said lever is provided with a cam w^4 , said cam acting against the sliding jaw in a manner to press the latter into firm contact with the pipe, whereby the pipe will be gripped between the fixed jaw and the sliding jaw in a manner to bend the lip on the pipe when the lever is pressed in a downward direction.

The tool of Fig. 18 is quite similar to some of the tools heretofore described, except that the means for limiting the movement of the lever is positioned externally of the pipe. Lever Z is enlarged so as to form a stop member z . This lever is provided with a jaw Z' adapted to enter the pipe, and another jaw Z^2 positioned to engage externally with the pipe. The jaw Z' may be made in one piece with the lever, or said jaw may be made in a separate piece which is attached to the lever by a screw z' . The tool is positioned upon the end portion of the pipe for the jaws Z' , Z^2 to engage internally and externally with said pipe, and when the lever is moved to the inclined position, the jaws coöperate in bending the lip on the pipe, whereas the stop member z is brought into contact externally with the pipe so as to limit the operative movement of the lever.

In Fig. 23 the pipe X is shown as having a single lip x' formed thereon by the operation of any one of the tools heretofore described. After bending the lip x' the tool may be shifted to another operative position so as to form the lip x^2 , shown in dotted lines in Fig. 23, and these operations may be repeated indefinitely until the end portion of the pipe is bent successively so as to result in a series of lips which produce a substantially continuous flange, as indicated at x^3 in Fig. 23. When the tool is provided with a jaw, the operative end of which is formed with a slot or groove v^4 , intersecting with the biting edge v^5 , as shown in Fig. 20, the pressure of the tool against the pipe will be divided between the biting edges, thereby decreasing the tendency to bend the wall of the pipe inwardly thereof at the point of bearing by the tool upon the pipe.

It should be noted that, in practically all forms of tool herein disclosed, the coöperating jaws are spaced relatively to each other, so as to receive, in the space thus provided, a wall of the pipe at one end thereof, the opposing surfaces of said jaws being curved to substantially conform to the surfaces of the pipe, a sufficient space being left or provided into which the metal of the pipe

can be deflected when pressure is applied by the lever, or its equivalent, to that jaw which is to be positioned internally of the pipe, said deflected metal producing a lip or lips on the end portion of the pipe.

Having thus fully described the invention, what I claim as new, and desire to secure by Letters Patent is:

1. A bending tool for forming a lip upon the end portion of a pipe embodying a lever, a pair of coöperating jaws spaced relatively to each other to receive a wall of a pipe at one end thereof, and means serving as a fulcrum for the lever whereby said lever operates to move one jaw thereof relatively to the other to bend the metal toward the other jaw.

2. A bending tool for forming a lip upon the end portion of a pipe embodying a lever, a pair of coöperating jaws spaced relatively to each other to receive a wall of a pipe at one end thereof, means positioned relatively to the lever to act as a fulcrum therefor in bending the wall of the pipe at one end portion thereof, and means coöperating with the lever, whereby, upon the operating of the tool, said lever operates to move one jaw thereof relatively to the other to bend the metal toward the other jaw.

3. A tool for bending a lip on the end portion of a pipe embodying a lever, and a pair of coöperating jaws operated by the lever to bend the metal on an end portion of a pipe, one of said jaws occupying a coöperative relation to the lever for limiting the movement thereof in the direction in which the lip is bent on the pipe, whereby said lever operates to move one jaw thereof relatively to the other to bend the metal toward the other jaw.

4. A tool for bending a lip on an end portion of a pipe embodying a lever, a pair of coöperating jaws, said jaws being provided with curved opposed surfaces and said jaws being spaced to produce between themselves a groove or slot adapted to receive the thickness of a pipe end to be bent into a lip, and a member in coöperative relation to the lever to serve as the fulcrum thereof when pressure is applied to the lever, whereby said lever operates to move one jaw thereof relatively to the other to bend the metal toward the other jaw.

5. A bending tool for forming a lip upon the end portion of a pipe, embodying a pair of coöperating jaws which are connected and spaced relatively to each other, and so formed that one jaw is adapted to engage with the end portion of the pipe on which the tool is adapted to coöperate interiorly thereof, and the other is adapted for simultaneous engagement with said pipe exteriorly thereof, a part of said jaw engaging with said pipe below that portion of the pipe which is to be bent, and means for op-

erating the interiorly positioned jaw laterally of the longitudinal axis of the pipe to apply pressure interiorly of the pipe for the purpose of bending a portion of the wall of the pipe outwardly.

6. A bending tool for forming a lip upon the end portion of a pipe, embodying a pair of coöperating jaws which are connected and spaced relatively to each other, and so formed that one jaw is adapted to engage with the end portion of the pipe on which the tool is adapted to coöperate interiorly thereof, and the other is adapted for simultaneous engagement with said pipe exteriorly thereof, a part of said jaw engaging with said pipe below that portion of the pipe which is to be bent, and means for operating the interiorly positioned jaw laterally of the longitudinal axis of the pipe to apply pressure interiorly of the pipe for the purpose of bending a portion of the wall of the pipe outwardly, that portion of the jaw which engages with the pipe, below the portion thereof which is to be bent, being adapted to limit the bending action of the tool for the purpose of precluding the formation of too great a bend.

7. A bending tool for forming a lip upon the end portion of a pipe embodying a pair of connected coöperating jaws the opposing surfaces of which are complementarily curved, and one of said jaws being longer than the other, and including an abutment against which the pipe is forced in the bending operation, whereby, when the tool is operated the longer jaw serves to preclude the formation of a bend of too great a lateral extension.

8. A bending tool for forming a lip upon the end portion of a pipe embodying a pair of coöperating jaws positioned in spaced relation, one of said jaws being longer than the other, and one of said jaws embodying a movable member adapted at all times to contact with the pipe being bent, means for operating said jaws, and means for limiting the degree of lateral extension formed on the pipe.

9. In a bending tool for forming a lip upon the end portion of a pipe, the combination of a lever, and a pair of coöperating jaws on said lever one of which is loosely mounted for engagement with the pipe at all times irrespective of the angular relation of the lever thereto, whereby said loose jaw serves as a fulcrum for the lever in the operation of the other jaw in forming a lateral extension from the wall of the pipe.

10. In a bending tool for forming a lateral extension upon the end of a tubular member, the combination with a lever having a fixed jaw adapted to be positioned in-

teriorly of the tubular member, and a movable jaw mounted on the lever and adapted to be positioned exteriorly of the tubular member, the operation of the lever causing the fixed jaw to move laterally of the longitudinal axis of the tubular member, exerting pressure interiorly of the wall and forcing a portion of said wall outwardly.

11. In a bending tool for forming a lateral extension upon the end portion of a pipe, a fulcrum member, a lever connected therewith, and an elongated jaw the lower end of which is adapted to contact with the pipe, when said pipe has been bent the desired distance, to preclude further bending of the pipe.

12. A bending tool embodying a lever, a pair of coöperating jaws positioned to receive between themselves a wall of a pipe at one end thereof, fulcrum means for said lever, and means for limiting the movement of the lever when the latter is operated to apply pressure to the internally positioned jaw.

13. A bending tool embodying a fulcrum member, a lever, a pair of coöperating jaws spaced relatively to each other to receive between themselves a wall of a pipe at one end thereof, and means for limiting the movement of the lever upon the operation of the latter in a direction to apply pressure to the internally positioned jaw for producing a lip upon the pipe at the end portion thereof.

14. A bending tool embodying a fulcrum member, a lever, a pair of coöperating jaws spaced relatively to each other to receive between themselves a wall of a pipe at one end thereof, the opposing surfaces of said spaced jaws being curved to grip the end portion of the pipe end, and means for limiting the movement of the lever upon the operation of the latter in a direction to apply pressure to the internally positioned jaw for producing a lip upon the pipe.

15. A bending tool for forming a lip upon the end portion of a tubular member embodying a lever provided with a pair of coöperating relatively movable spaced jaws adapted to engage opposite sides of a wall of the tubular member, movement of the lever serving to effect relative movement of the jaws and thereby to bend a portion of the end of the tubular member.

In testimony whereof I have signed my name to this specification in the presence of two subscribing witnesses.

JOHN N. SCISM.
